COMBINED CASTER AND MOUNTING

Alan W. Speicher, Evansville, and Michael G. Forman, Newburgh, Ind., assignors to Bliss & Laughlin Industries, Incorporated, Oak Brook, Ill.

Filed Oct. 23, 1969, Ser. No. 19,685

Term of patent 14 years

Int. Cl. D8—03

U.S. Cl. D8—226

FIG. 1.

FIG. 2.

FIG. 3.

FIG. 4.

FIG. 5.

FIG. 1 is an elevational view of combined caster and mounting showing our new design.

FIG. 2 is a rear elevational view of one of said caster mountings.

FIG. 3 is a front elevational view of one of said caster mountings.

FIG. 4 is a top plan view thereof.

FIG. 5 is a bottom plan view thereof.

The broken lines are for illustrative purposes only.

We claim:

The ornamental design for a combined caster and mounting, as shown and described.
